UNITED STATES PATENT OFFICE.

ADAM RICHARDSON, OF ELBA, AND BERT B. JACKSON, OF ALMYRA, ARKANSAS; SAID RICHARDSON ASSIGNOR TO SAID JACKSON.

WORK-SUPPORT.

1,244,374.

Specification of Letters Patent. Patented Oct. 23, 1917.

Application filed June 16, 1916. Serial No. 104,059.

To all whom it may concern:

Be it known that we, (1) ADAM RICHARDSON and (2) BERT B. JACKSON, citizens of the United States, residing at (1) Elba, (2) Almyra, in the county of (1) Van Buren, (2) Arkansas, and State of Arkansas, have invented certain new and useful Improvements in Work-Supports; and we do hereby declare the following to be a full, clear, and 10 exact description of the invention, such as will enable others skilled in the art to which it appertains to make and use the same.

The invention relates to a wheel boring machine.

15 The object of the present invention is to improve the construction of wheel boring machines and to provide a simple, practical and comparatively inexpensive device of this character adapted to be readily applied 20 to the post or support of a force feed drill or boring machine and equipped with a combined support and spindle adapted to receive either the hub or felly of the wheel and capable of rapid and accurate adjustment to arrange the wheel in proper position 25 with relation to the drill or boring machine and capable of enabling tenons to be accurately and uniformly bored on the ends of spokes and of boring accurately the 30 holes in fellies for the reception of the spoke tenons.

With these and other objects in view, the invention consists in the construction and novel combination of parts hereinafter fully 35 described, illustrated in the accompanying drawings and pointed out in the claims hereto appended; it being understood that various changes in the form, proportion, size and minor details of construction, within 40 the scope of the claims, may be resorted to without departing from the spirit or sacrificing any of the advantages of the invention.

In the drawings

45 Figure 1 is a side elevation of a wheel boring machine constructed in accordance with this invention,

Fig. 2 is a horizontal sectional view the combined support and spindle being shown 50 in plan view,

Fig. 3 is a front elevation of the attachment,

Fig. 4 is a vertical sectional view of the same,

Fig. 5 is a transverse sectional view of a 55 spindle, the hub being shown in position,

Fig. 6 is a detail perspective view of the post plate,

Fig. 7 is a similar view of one of the adjustable felly gages, 60

Fig. 8 is a detail view illustrating the manner of tenoning a spoke,

Fig. 9 is a detail perspective view of one of the arms.

Like numerals of reference designate corresponding parts in the several figures of the drawings.

In the accompanying drawings in which is illustrated the preferred embodiment of the invention, 1 designates a post plate preferably consisting of a casting and bolted or otherwise secured to a post 2 below a force feed drill 3 and provided at opposite sides of its center with vertical slots 4 through which extend arms 5 of a combined support 75 and spindle 6 adapted to receive the hub 7 or felly 8 of a wheel and capable of vertical adjustment to arrange the felly and the hub in proper position with relation to the drill. The drill as illustrated in Fig. 8 is also 80 adapted for operating on the spokes 9 for boring tenons which may be accurately and uniformly made to fit the holes bored in the felly 8. The post plate is preferably provided at the back with cored central and 85 side recesses 10 and 11 both to lighten the construction and also to provide clearance spaces for the heads 12 of the arms 5. The heads 12 form laterally projecting lugs 13 which have rounded front faces 14 to bear 90 against the inner or rear face of the post plate at opposite sides of the vertical slots 4. The post plate is machined or otherwise dressed to form smooth true faces at the slots and the arms 5 are provided with inner and outer slots 15 for the reception of bolts 16 having nuts 17 for engaging the outer faces of the arms which are provided with corrugations 18 whereby the bolts and nuts are effectually prevented from permitting any accidental slipping of the spindle or support. The spindle or support is adjusted by means of the bolts 16 and slots 15 to compensate for any wear of the parts and arrange the spindle at the proper pitch or inclination when such adjustment is necessary.

The support or spindle which is tapered outwardly to fit the axle box of the hub is

preferably constructed of hard wood but it may be made of any other suitable material and it is equipped at its inner or rear end with a heel plate 19 suitably secured to the spindle or support and provided at its lower edge with a beveled rib or enlargement 20, which is adapted to engage spiral or rasp teeth 21 formed on the front face of the post plate and extending across the space between the vertical slots and presenting horizontal upper faces or shoulders and inclined lower faces. By this construction the transverse rib or tooth which is located below the horizontal plane of the heads of the arms is adapted to be readily swung forwardly out of engagement with the rasp face of the post plate by lifting the outer portion of the spindle. This will enable the spindle to be easily and quickly adjusted and arranged at the desired elevation. The post plate is provided at the space between one of its vertical slots and its side edges with graduations 22 preferably cast in the surface of the post plate but they may be applied to the same in any other desired manner as will be readily understood.

The support or spindle is provided in its outer portion with a vertical opening 23 adapted to receive the drill bit and it has a recess 24 in its upper face presenting a flat face to a felly to form a rest therefor and receiving a pair of felly gages 25. The felly gages 25 each consist of a plate or body portion provided with an upwardly extending flange 26 and secured in its adjustment by a bolt 27 operating in a slot 28 in the plate or body portion and piercing the spindle or support and provided at its lower

end with an adjusting nut 29 which is countersunk in a lower recess 30 in the lower face of the spindle or support. The felly gages are adapted to be adjusted to suit the width of a felly and they are provided with central longitudinal ribs or lugs 31 operating in grooves 32. The lugs or ribs maintain the gages in proper position for accurately guiding the felly so that the tenon receiving openings will be true. The gages and their flanges which are segmental are located within the contour of the spindle or support and a hub is adapted to be passed over them without contact with either the gages or fastening means for securing the gages in their adjustment.

What is claimed is:—

1. A work holder including a spindle arranged to receive and support the hub of a wheel, said spindle being provided between its ends with a felly rest located within the contour of the spindle to permit a hub to pass over it.

2. A work holder including a spindle arranged to receive and support the hub of a wheel, said spindle being provided between its ends with a recess forming a felly rest, and adjustable gages arranged within the said recess and located within the contour of the spindle to permit a hub to pass over them.

In testimony whereof we affix our signatures in presence of two witnesses.

ADAM RICHARDSON.
BERT B. JACKSON.
